MAX JAEGER, OF BROOKLYN, NEW YORK, ASSIGNOR TO ANCHOR CAP & CLOSURE CORPORATION, OF BROOKLYN, NEW YORK, A CORPORATION OF NEW YORK.

HERMETIC SEAL AND METHOD OF MAKING SAME.

Application filed May 3, 1924. Serial No. 710,722.

The present invention relates broadly to the art of packaging, and more especially to a hermetic seal and the method of making same.

- 5 Heretofore in the art, hermetic seals have generally been made in two ways; first, arranging a gasket on a suitable container and then forcing a closure cap downwardly over the gasket to distort the same and form 10 a hermetic joint between the closure cap and the container. This method required an operation which comprised placing the gasket in position on the container and in view of the difficulty of handling plastic gaskets 15 this operation required hand manipulation, which is not desirable in this age of automatic machinery. The other method in common use comprised applying a cap, with a gasket therein and carried thereby, over a 20 slightly smaller diameter mouth of a suitable container and then positively distorting the bead of the cap to tightly force the gasket radially against the glass and thereby provide the required seal. This method 25 comprises a very efficient way of applying a closure but necessitates sealing forces of sufficient magnitude to occasionally cause breakage of the container. In caps of this type the seal is preferably made slightly below the mouth of the container and therefore 30 the cap must be provided with a depending flange carrying the bead, which is of sufficient length to permit the sealing zone to be located on the side wall of the container below the mouth of the container. 35 In seals of this character it is desirable that the sealing surface shall be substantially cylindrical and in view of the fact that this portion of a glass container is formed by the 40 ring mold of a glass mold, which must be lifted from the formed article, it is difficult to manufacture containers with such cylindrical surfaces, because the cylindrical form does not permit of sufficient draw to 45 enable the ring mold to be lifted easily.

The present invention overcomes the difficulties of the known art by providing a hermetic seal and method of making same which embodies the advantages of both of 50 the prior methods specified, and avoids the disadvantages heretofore attended thereto. In the present invention a hermetic seal is formed adjacent the mouth of the container by forcing thereover a closure cap carrying

a suitable gasket in such manner that the 55 gasket slides downwardly over a conical surface adjacent the mouth of the container and a portion of the gasket interlocks beneath a ledge or shoulder on the container and above a supporting member on the lower edge 60 of the cap, which may comprise a solid rigid wire edge that may be formed by tightly coiling the edge of the skirt of the cap inwardly and upon itself. Preferably the inclined conical surface on the container is 65 wetted just prior to applying the cap so that the elastic gasket, preferably of a rubber composition, slides downwardly over the conical surface and expands beneath the ledge or shoulder on the container when the parts 70 are completely telescoped. The telescoping operation may be carried out by a supporting chuck or head which moves parallel to the axis of the container and which may be provided with a supporting rim which prevents undue distortion of the skirt of the cap during the sealing operation.

After having generally described the present invention in certain aspects, it may be stated that the principal object of the present invention is to provide a hermetic seal for closures and the like comprising a closure cap with a depending skirt having a supporting ledge for a gasket combined with a container having a conical ring adjacent 85 the mouth thereof and a locking edge beneath the lower portion of the said ring.

An equally important object of the present invention is the method of forming hermetic closures which comprises providing a 90 container having an inclined surface adjacent the mouth thereof, wetting said surface, and telescoping a suitable closure carrying an elastic gasket over said wetted surface to wedge the gasket material between 95 the mouth of the container and the skirt of the cap, thereby forming a hermetic seal.

Other and further objects of the present invention will in part be obvious and will in part be pointed out hereinafter in the specification following by reference to the accompanying drawings forming a part thereof.

Realizing that the present invention may be embodied in structures and carried out by steps other than those specifically disclosed, it is desired that the disclosure here-with shall be considered as illustrative and not in the limiting sense.

Figure 1, of the drawings is an elevational view of a sealed package according to the present invention.

Figure 2, is a sectional view of a suitable container and a cap prior to the application of the cap to a container.

Figure 3, is a sectional view showing a container sealed according to the present invention.

10 Figure 4, is a detail sectional view showing the relation of the gasket on the side wall of the container prior to sealing and illustrating a portion of a sealing head adapted to seal caps in accordance with the 15 present invention.

Figure 5, is a detail view illustrating a section through a portion of the skirt of the cap, the gasket, and the side wall of the container, after the seal has been made.

20 Referring now to the drawings, which illustrate a preferred embodiment of a cap and sealed package in accordance with the present invention, the cap comprises a cover portion 1, which preferably has a depending center 2, to form an annular shoulder 4. A substantially cylindrical skirt 5 depends at right angles from the cover portion and preferably terminates in a tightly coiled inturned wire edge 6 which provides a lower 25 supporting member for a suitable gasket 7. Preferably this gasket comprises an annular ring of rubber composition or other suitable plastic material, and the gasket preferably is of substantially a rectangular cross-section, so that it is supported between the 30 inturned wire edge 6 and the annular shoulder 4, thereby securely holding the gasket in place in the cap during handling and transporting of the caps. This cap and 35 gasket therein is adapted to be placed upon the mouth of a suitable container 8 which is preferably finished adjacent the mouth thereof with a conical sealing portion 9 that terminates in a shelf or ledge 10 which is 40 spaced below the end of the container of a distance which is less than the length of the gasket 7.

45 Preferably the conical sealing surface 9 is wetted sufficiently to form a film of liquid 50 over the surface to comprise a lubricant to prevent the gasket from sticking to the surface during the sealing operation. The sealing operation may be carried out by causing a telescoping movement between the closure 55 and the container. This may be effected by the use of a suitable sealing chuck 11, which may comprise a head portion that carries a cushion 14, such as rubber, or the like, and a work face 15, which may be formed of 60 fibre or other suitable material. This chuck preferably is provided with a depending rim 16 having an internal diameter slightly greater than the external diameter of the skirt of the cap to be applied. This rim 65 16 does not distort the bead of the cap, but

on the contrary supports the bead against distortion by internal forces when the cap is being forced over the container. When the chuck is placed over a cap setting loosely on the wetted conical portion on the container and pressure is applied to the chuck, the gasket 7 will be distorted and will slide down over the conical surface, which operation will continue until the end of the container contacts with the cover portion of the cap. As soon as the lower portion of the gasket passes the ledge 10 on the container, the portion of the gasket beneath the ledge being freed from compressive forces, will expand beneath the ledge and will extend 70 between the ledge and wire edge 6 in the form of an inwardly extending locking ring 17, thereby securely locking the cap in position on the container.

75 From the foregoing construction it will be observed that if internal forces are exerted against the cover portion of the cap, there will be a tendency to pull the skirt of the cap inwardly at the top part thereof, and in view of the fact that the lower edge 80 of the skirt is securely held from expanding by means of the wire edge, the gasket material between the container and the skirt of the cap will be further compressed and the interlocking action between the cap and the container will be increased, thereby more 85 securely locking the cap to the container.

90 Having thus described my invention, what I claim is:

1. A closed package comprising a closure 100 cap having a cover portion, a skirt depending from said cover portion, a ring shaped gasket supported by said skirt, in combination with a suitable container having a sharp edged locking shoulder adjacent the mouth 105 of the container and with the external diameter of said locking shoulder being greater than the internal diameter of said gasket ring before the cap is applied, and means on said closure cap supporting said gasket ring adjacent said shoulder and maintaining a portion of said gasket ring under said shoulder without necessitating deformation of said closure, thereby interlocking said cap without deformation thereof with said container and forming a hermetic seal.

110 2. The method of hermetically sealing packages, comprising a closure cap having a skirt carrying an elastic gasket ring and a container having a conical sealing zone adjacent the mouth thereof which terminates in a locking ledge of greater external diameter than the internal diameter of the said gasket, which method comprises providing a film of lubricating liquid between the sealing zone of the container and the gasket and then telescoping the closure cap over the container to compress the gasket and interlock the gasket and the ledge on the container.

3. The method of forming hermetic seals between a closure cap having a cover portion, a skirt depending from said cover portion, a reinforcing edge at the bottom of said skirt, and an elastic gasket above said reinforcing edge and a container having a substantially incompressible side wall with an inclined sealing zone adjacent the mouth of the container and terminating in an interlocking shoulder which is larger than the normal internal diameter of said gasket, which method comprises wetting said sealing zone and forcibly telescoping said cap relatively to said container to compress the gasket between the side wall of the cap and the container and to position a portion of the gasket under the locking ledge on the container.
4. The method of forming hermetic seals between a closure cap having a cover portion, a skirt depending from said cover portion, a reinforcing edge at the bottom of said skirt, and an elastic gasket above said reinforcing edge and a container having a substantially incompressible side wall with an inclined sealing zone adjacent the mouth of the container and terminating in an interlocking shoulder, which method comprises wetting said sealing zone and forcibly telescoping said cap relatively to said container, and causing said gasket to slide downwardly over the sealing zone to compress the gasket between the side wall of the cap and the container and releasing the pressure on the portion of the gasket extending toward the container under the shoulder while supporting the full length of the gasket by the cap skirt thereby causing the gasket to expand under the shoulder.
5. As an article of manufacture, a vessel having a smooth annular surface extending conically from the mouth of the vessel to facilitate application of a ring gasket smaller than the maximum circumference of said conical surface, said surface ending abruptly to form a sharp annular locking projection adapted to interlock with a gasket expanded thereover to hold a closure cap in place.
6. The method of forming a sealed package which comprises providing a rigid walled vessel having a surface extending conically from the mouth thereof and ending abruptly in an annular locking edge, providing a closure cap, providing a gasket having a normal internal diameter which is less than the diameter of the annular locking edge, interlocking the gasket with the closure cap, and then telescoping the cap and gasket over the conical surface and the locking edge to compress part of the gasket against the conical surface to form a seal, and to interlock the gasket under the annular locking edge.
7. The method of forming a sealed package which comprises providing a rigid walled vessel having an outwardly extending annular surface near the mouth thereof, said outwardly extending surface ending abruptly in an annular locking edge; providing a closure cap; providing a gasket having a normal internal diameter which is less than the diameter of the annular locking edge; interlocking the gasket with the closure cap; and then telescoping the cap and gasket over the outwardly extending surface and the locking edge to compress part of the gasket against the outwardly extending surface to form a seal, and to interlock the gasket under the annular locking edge.
8. A sealed package comprising a rigid walled vessel having adjacent its mouth an annular outwardly extending surface ending abruptly in an annular locking edge; a cap having a skirt portion surrounding said locking edge and spaced therefrom; a substantially rectangular gasket between said skirt portion and said outwardly extending surface of the vessel, said gasket having a normal internal diameter which is less than the diameter of the locking edge and said gasket being stretched over and interlocked under said locking edge and held against said outwardly extending surface by the resiliency of the gasket and by compression of the gasket between the skirt portion and the container; and an inturned wire edge at the bottom of the skirt portion locking said cap to the gasket.
9. A sealed package comprising a vessel having adjacent its mouth an annular outwardly extending surface ending abruptly in an annular locking edge; a gasket having a normal internal diameter which is less than the diameter of the locking edge, said gasket being stretched over said locking edge whereby the resiliency of the gasket acts to hold it interlocked under said locking edge and also against said outwardly extending surface to form a seal; and a closure cap associated with said gasket.
10. A sealed package comprising a vessel having adjacent its mouth an annular outwardly extending surface ending abruptly in an annular locking edge; a gasket having a normal internal diameter which is less than the diameter of the locking edge, said gasket being stretched over said locking edge whereby the resiliency of the gasket acts to hold it interlocked under said locking edge and also against said outwardly extending surface to form a seal; and a closure cap having a skirt which embraces said gasket and holds it compressed thereby supplementing the resiliency of the gasket in holding it interlocked with the locking edge and against the outwardly extending surface to form a seal.

MAX JAEGER.
